UNITED STATES PATENT OFFICE.

ANTHONY RECKENZAUN, OF PHILADELPHIA, PENNSYLVANIA, ASSIGNOR OF ONE-HALF TO JAMES A. PENTZ, OF SAME PLACE.

ELECTRIC METER.

SPECIFICATION forming part of Letters Patent No. 394,881, dated December 18, 1888.

Application filed April 14, 1888. Serial No. 270,696. (No model.)

To all whom it may concern:

Be it known that I, ANTHONY RECKENZAUN, of London, England, a subject of the Queen of Great Britain, temporarily residing at 5 Philadelphia, in the county of Philadelphia and State of Pennsylvania, have invented certain new and useful Improvements in Electric Meters; and I do declare the following to be a full, clear, and exact description of the invention, such as will enable others skilled in the art to which it appertains to make and use the same, reference being had to the accompanying drawings, and to the letters and figures of reference marked thereon, which form a part 15 of this specification.

The invention relates to electric meters in which the amount of electrical energy flowing through a given circuit in a given time is measured; and it has for its objects to periodically release contact between parts of the variable-speed gear employed to move the registering devices, so that said parts may assume the position they should have relatively to the energy consumed.

25 It further has for its object to compensate for the varying attractive force of a solenoid on an iron core, which, as is well known, is not always in exact proportion to the current's strength employed.

30 To the accomplishment of the above and such other objects as may herein appear, the invention will be hereinafter particularly described, reference being had to the accompanying drawings, forming a part hereof, and 35 in which—

Figure 1 is a side elevation, with parts in section; Fig. 2, an end elevation, with parts in section.

The instrument consists, essentially, of a 40 motor, capable of turning the registering mechanism. This motor may be any suitable means. It may be a device worked by springs or by compressed air or raised weights, or any other kind of power; but it is preferred to utilize 45 an electric motor for this purpose. Such electric motor, of any known construction and represented by A, is connected in shunt to the main current by means of thin wires a a. The armature and field magnets of such motor will be wound in such a manner that the 50 speed of the motor is constant with a con-

stant potential at the terminals B B' of the meter or instrument. The motor A carries on its spindle a worm, C, which gears into a worm-wheel, D, which is "faced" on one side. 55 Against this face works a friction wheel or roller, E. This friction-roller is attached to a tube, F, say, of brass. This brass tube is feathered upon the steel spindle or shaft G, and is capable of sliding up and down. In 60 order that the spindle G may revolve with the brass tube F, a pin, b, is put into spindle G, which pin projects through a long slot, c, in tube F. This slot allows the brass tube to slide up and down if pressure is applied to it. 65 Upon the upper end of spindle G is placed another worm, H, which actuates worm-wheel I, to which a train of wheels, as 1 and 2, is geared.

J represents a tube or core of wrought-iron, attached to brass tube F by suitable means— 70 say by set-screw e.

K represents a wire coil or solenoid. Whenever a current is passing through the solenoid K, the solenoid will suck the iron J into it, and the greater the current the stronger will 75 be this attraction or suction. The shaft d of worm-wheel D is journaled in a suitable box, L, and against its end bears an arm or spring-plate, M, the pressure of which against the end of the shaft d to keep the worm-wheel 80 and friction-roller in contact may be regulated by a screw or a thumb-nut, N, on a pin, O, having its bearing in the post of the boxing L.

The framing P may be of any suitable construction, and a screw, Q, may be employed 85 to center and hold shaft G on its step R.

The parts so far described are the same as shown and described in the application filed by myself and James A. Pentz, January 20, 1888, Serial No. 261,405, and I will now proceed to describe the improvements thereon.

Under the construction described in said application referred to, if the current was weakened or the consumption of its energy lessened—say, by taking out one or more lamps— 95 the frictional contact of the roller E with the worm-wheel D was apt to hold the wheel E at the point where it touched when more energy was being consumed, and consequently the device was not as acutely sensitive as desirable. To overcome that difficulty, I provide 100 suitable means for releasing contact between

the friction-wheel and worm for a period sufficient to give the friction-wheel an opportunity to drop or assume the position it should have relatively to the energy consumed, such 5 relief being made to occur as often as desired. As an illustration of means suitable therefor, I form one or more cams, *f*, on the bearing for the shaft *d*, and on that shaft I place a pin, *g*, which will be brought against the cam in 10 the revolution of the shaft of the worm-wheel *D*, so that as often as the two parts are brought in contact the wheel *D* will be moved from contact with the friction-roller, and the latter thus given an opportunity to assume its proper 15 position. The spring *M* will restore the worm-wheel into contact with the friction-roller. The pressure of said spring may be regulated by the nut *N*.

As herein previously stated, the varying 20 attractive force of a solenoid on an iron core is not always in exact proportion to the current's strength employed. In order to compensate these irregular effects, I employ a second similar solenoid, which acts on an 25 other iron core, and therefore the disproportion of the two will produce a proportional or approximately proportional result. With that end in view I employ a solenoid, *K'*, in circuit with the first solenoid, *K*, in which sec- 30 ond solenoid a core, *J'*, is suspended from a lever, *S*, said lever being fulcrumed, say, upon standard or post *T*, and at its opposite end connected with the friction-wheel *E*, or with the sleeve connecting with the core *J*, so that 35 as the attraction on core *J* varies or changes while the core changes its position in the solenoid the varying attractive force is compensated for by the influence of the solenoid *K'* on the core *J'*, which establishes an equilib- 40 rium at opposite ends of the lever, and yet at the same time determines the exact position of the friction-roller relative to the worm-wheel when any given amount of energy is being measured.

45 The *modus operandi* is as follows, viz: Terminals *B* and *B'* of the meter will be joined to any electric-supply circuit the energy of which it is desired to measure. As soon as the current is switched on, and not until then, the 50 constant speed-motor *A* will revolve. Let it be assumed that no current is required by the main circuit. The motor *A* then will only consume a very small fraction of energy necessary for its own propulsion, and at such time 55 the friction-roller *E* will be in the center of worm-wheel *D*, its normal position. When the flow of current is caused by electric lamps or other energy-consuming apparatus being put in action, the core *J* will be sucked up 60 into the solenoid *K*, and simultaneously the friction-roller *E* will be raised out the center of worm-wheel *D*, which keeps on revolving and causes the roller *E* to revolve with it. The greater the current in the solenoid *K* the 65 further will the core be sucked into the solenoid *K* and the friction-roller *E* be moved away from the center of the worm-wheel *D*.

The influence of the solenoid *K'*, however, on its core *J'* compensates the varying attractive force of the solenoid *K* on its core *J*, as the latter changes its position in its solenoid, and so an equilibrium is established between the two ends of the lever and the proper position of the friction-roller determined. The speed of worm *C* being constant, the revolutions of 70 friction-roller *E* and spindle *G* will be in proportion to the radial displacement of wheel or roller *E*. Consequently the more energy there is consumed the faster will roller *E* and everything attached to it run, so that there is 75 formed a variable speed-gear, and as often as the worm-wheel is moved away from the friction-roller by the cam acting on the pin *g* the friction-roller is given an opportunity to drop in proportion to the reduction in the 80 energy consumed, and thus caused to assume 85 its proper position for the energy consumed. Worm-wheel *I* drives the set of wheels 1 and 2, provided with the pointers or hands 3 and 4, which will indicate on a suitable scale 90 formed, say, on the face of the train-wheels, the number of revolutions per hour or per day, or any convenient unit of time. The train of wheels, pointers, and scales may be arranged in any well-known way, so that one 95 will show units, another tens, another hundreds, &c., and the parts of the instrument are so proportioned that given numbers of revolutions of the pointers will indicate a corresponding number of lamp-hours, or ampère-hours, or horse-power hours, as the case 100 may be.

Having described my invention and set forth its merits, what I claim is—

1. In an electric meter, the combination, 105 with a variable-speed gear, of means for periodically releasing contact between parts of said speed-gear, substantially as and for the purposes set forth.

2. The combination, with the wheel having 110 a friction-roller changing its point of contact with said wheel with the change in the consumption of energy, of means for periodically releasing contact between said friction-roller and wheel, substantially as described. 115

3. In an electric meter, the combination, 120 with a solenoid energized from the main current, of a second solenoid in circuit with the first solenoid and connected with said solenoid to compensate for the varying attractive force of one solenoid, a variable-speed gear having its speed varied by the energy to be measured, and a constant-speed motor for moving said gear, substantially as and for the purposes described. 125

4. The combination, with the wheel having 130 a friction-roller changing its point of contact with said wheel with the change in the consumption of energy, of a solenoid energized from the main current and moving said friction-wheel and a second solenoid in circuit with the first solenoid and connected with a part of said friction-wheel-moving mechanism to counterpoise or compensate for the

varying attractive force of one solenoid on its core and thus establish an equilibrium, substantially as and for the purposes set forth.

5. In an electric meter, the combination, with the two solenoids in circuit with each other, of the constant-speed wheel, the variable-speed roller, the shaft connecting with the registering mechanism and having motion transmitted to it from said variable-speed roller, and the lever intermediate of said

solenoids and having connection with parts of the two solenoids, substantially as and for the purposes set forth.

In testimony whereof I affix my signature in presence of two witnesses.

A. RECKENZAUN.
